[57] ABSTRACT

Disclosed herein is an oil pumping system or arrangement including a piston which is arranged for rotating and reciprocating movement in a pumping chamber to effect pumping operation, together with means communicating with the pumping chamber for signaling the absence of oil in the system. The piston and the pumping chamber include means for effecting supply and discharge of oil in response to rotary and reciprocating movement of the piston. Such means includes two axially adjacent flats on the piston and location of the inlet and outlet ports in the pumping chamber in axially spaced relation so that both of the inlet and outlet valves are closed during a portion of the piston travel on the compression stroke, whereby to generate a pumping pressure which is utilized in the signaling system. Also disclosed herein is means for reciprocating the pumping piston in response to rotation thereof and for varying the length of piston pumping reciprocation independently of the speed of piston rotation.

CHAIN SAW WITH OIL PUMPING AND SIGNALING ARRANGEMENT

BACKGROUND OF THE INVENTION

For some time chain saws have been provided with oil pumping arrangements for supplying oil from a reservoir to a cutting chain. Some chain saws having included automatic pumping arrangements but such arrangements lacked any capability for warning the operator of an absence of oil in the pumping system. Thus, it was possible for the operator to continue use of the saw without realizing the absence of lubricating oil and therefor run the risk of damaging the saw chain and cutter. In the prior automatic pumping systems, inlet and outlet ports were located in opposing relation to each other and were transversed by a flat on the piston to effect pumping action. However, all of the prior art devices have been without any arrangement for automatically pumping oil to the saw chain and for informing the operator of an absence of oil in the pumping system.

SUMMARY OF THE INVENTION

The invention provides a pumping arrangement or system including automatic signaling means for informing the operator of an absence of oil in the pumping system. In one disclosed construction, the absence of oil in the pumping system is indicated by the illumination of a light. Other arrangements are also within the over-all context of the invention.

The invention also provides an arrangement where the signaling means is biased to afford indication of an absence of oil in the lubricating system, together with an arrangement for overpowering the biasing means to avoid signaling the operator in response to the development of pumping pressure in the pumping system.

The invention also provides a pumping arrangement which includes a rotary and reciprocating piston for effecting pumping operation and which is designed so that a period of reciprocation occurs during the compression stroke and prior to the opening of the outlet port to generate pumping pressure and to effect displacement of a plunger operating the signaling means. In this regard, in accordance with the invention, the piston includes two axially adjacent flats which have a common edge but differing angular extent, and which are respectively associated with the inlet and outlet ports.

Also in accordance with the invention, the pumping arrangement is provided with means for reciprocating the piston in response to piston rotation and for varying the extent of piston reciprocation independently of the rate of piston rotation.

One of the principal objects of the invention is the provision of a superior oil pumping arrangement or system for a saw chain, which arrangement includes means for signaling the operator when there is an absence of oil in the pumping system.

Another of the principal objects of the invention is the provision of a signaling device for an oil pumping arrangement in a chain saw, which device includes a light, together with normally closed switch means connecting the light to a source of power, such as a magneto or battery, and means responsive to the development of the pumping pressure to maintain the switch means in open position, thereby avoiding energizing

the light, until an absence of oil develops in the pumping system.

Another of the principal objects of the invention is the provision of a pumping system or arrangement in which a reciprocating and rotary piston is operative to move inwardly of a pumping chamber between closure of an inlet port and opening of an outlet port, thereby to generate pressure which can be utilized in a signaling means adapted to warn the operator of an absence of oil in the oil pumping system.

Another of the principal objects of the invention is the provision of an oil pumping arrangement including means for reciprocating a piston in response to piston rotation and for varying the length of piston reciprocation independently of the speed of piston rotation.

A still further object of the invention is the provision of a simple and economical pumping system or arrangement which will provide a long and useful life, which is especially adapted to use in a chain saw, and which will effectively signal the operator to warn of an absence of oil in the oil pumping system.

Other objects and advantages of the invention will become known by reference to the following description and accompanying drawings.

DRAWINGS

FIG. 1 is a perspective view of a chain saw embodying various of the features of the invention.

FIG. 2 is a schematic perspective view of various of the components included in the chain saw shown in FIG. 1.

FIG. 3 is an enlarged sectional view of a portion of the apparatus shown in FIG. 2.

FIG. 4 is an enlarged fragmentary view partially in section of another portion of the components shown in FIG. 2.

FIG. 5 is a side view of the structure shown in FIG. 4, partially broken away and in section, along line 5-5 of FIG. 4.

FIG. 6 is a wiring diagram of the electrical circuit embodied in the saw chain shown in FIG. 1.

FIG. 7 is an enlarged fragmentary view, partially in section, of a portion of the device shown in FIG. 3.

FIGS. 8, 9, 10, 11, 12, 13, and 14 are schematic views showing the sequential operation of the pumping structure shown in FIG. 3, with FIG. 8 being taken generally along line 8-8 of FIG. 8A and with the other views having a similar orientation.

FIGS. 8A, 9A, 10A, 11A, 12A, 13A, and 14A are schematic end views illustrating the position of the pumping components in FIGS. 8 through 14 respectively.

FIG. 15 is a schematic view of another pumping arrangement embodying various of the features of the invention.

FIG. 16 is a sectional view taken generally along line 16-16 of FIG. 15.

DETAILED DESCRIPTION

Shown in the drawings is a chain saw 11 which includes an oil pumping system or arrangement 13 (See FIG. 2) in accordance with the invention. The chain saw 11 includes a frame 17 supporting an engine 19 (shown fragmentarily in FIG. 2) having an output shaft 21 and an ignition system (not shown) powered by a

magneto 22 (See FIG. 6). The frame 17 also supports a cutter bar 23 around which is trained a saw chain 27 drivingly engaged by a sprocket (not shown) driven by the engine output shaft 21. In addition, the frame 17 also supports a lubricating oil reservoir 29 (See FIG. 2) communicating through a duct 31 with the oil pumping arrangement 13 which, in turn, communicates through a duct 33 having an outlet 37 adjacent to the cutter bar 23 to effect supply of lubricating oil to the saw chain 27.

In general accordance with the invention, the oil pumping arrangement 13 generally includes an oil pumping means or system and signal means operable to indicate a lack of oil in the pumping means or system. The oil pumping system comprises a housing 39 (See especially FIG. 3) supported by the frame 17 and including a pumping chamber 41, a pumping piston 43 extending into the pumping chamber 41, means 47 for rotating the piston 43 in the pumping chamber 41, and means 49 for reciprocating the piston 43 in the pumping chamber 41, whereby to effect pumping operation incident to reciprocating and rotating action. The signal means comprises means communicating with the pumping chamber and including an indicator light 51 (See FIG. 6) for signaling the absence of oil pressure normally generated by rotary and reciprocating pumping operation of the piston 43. Still further, the signaling means includes normally closed switch means 53 (See FIGS. 2 and 6) connected to the indicator light 51 and to a source of electrical power and means 57 operably connected to the switch means 53 for opening the switch means 53 in response to oil pressure generated in the pumping chamber 41, whereby the indicator light 51 is illuminated when there is an absence of oil pressure in the pumping chamber 41 even though the engine 19 is operating.

The pumping operation provided by the piston 43 and the pumping chamber 41 is afforded by cooperating means on the pumping chamber and on the piston for effecting supply and discharge of oil through the ducts 31 and 33 in response to rotary and reciprocating movement of the piston 43. In the disclosed construction, the means 49 for reciprocating the piston 43 includes means for effecting piston reciprocation in response to piston rotation and for varying the distance through which the piston reciprocates.

More particularly, the pumping system includes (See FIG. 3 and FIGS. 8 through 14) in the frame or housing 17 a bore 59 which, in part, forms the pumping chamber 41. At one end, the bore 59 is closed by means including a bushing 61 having an axial bore 63 and by a plunger 67 which is reciprocable in the bore 63 and forms a part of the signaling means. The pumping chamber 41 is further defined by the rotatable and axially reciprocable piston 43 extending into the bore 59.

Opening into the bore 59 and communicating with the pumping chamber 41 in diametrically opposed and axially spaced relationship are an inlet port 69 communicating with the duct 31 and an outlet port 71 communicating with the duct 33. The inlet port 69 is located adjacent to the end of the pumping chamber 41 formed by the bushing 61 and in position to be opened and closed in response to piston rotation. The outlet port 71 is also located so as to be opened and closed by the piston in response to piston rotation.

Cooperating means are provided on the piston 43 and on the pumping chamber 41 to effect periodic opening and closing of the inlet and outlet ports 69 and 71, respectively, and thereby to effect pumping action from the reservoir 29, through the pumping chamber 41 and to the outlet 37 in response to piston reciprocation and rotation. While various arrangements can be employed, in the disclosed construction, the piston 43 includes (See FIGS. 8 and 8A) a main cylindrical portion 73, together with an inner end portion 77 which extends from the main cylindrical portion 73 and an outer end portion 79 which extends from the inner end portion 77. The inner end portion 77 is cylindrically shaped, except for the provision of a flat 81 which subtends an angle of about 60 degrees. The flat 81 extends axially for a distance approximately equal to the axial distance between the inlet and outlet ports 69 and 71 respectively and the piston reciprocation arrangement is such that the piston 43 reciprocates relative to a position in which the outlet port 71 communicates with the bore 59 at a point adjacent to the inner end of the flat 81 when the piston 43 is at its most retracted position. Furthermore, it is to be understood that the maximum axial travel of the piston 43 is about the same as, and is not greater than, the axial length of the flat 81. Thus, during operation, the piston reciprocation is so limited that the inner end portion 77 is always opposed to the outlet port 71 and so that the outlet port 71 is opened during travel of the flat 81 therewith and is closed at all other times by the cylindrical surface portion 83 of the inner end portion.

The outer end portion 79 is slightly greater than semi-cylindrical in shape having a flat 87 which subtends an angle of just less than 180 degrees as shown in FIG. 8A. The flat 87 includes an edge 89 which is axially in register with the trailing edge of the flat 81 as determined by the piston rotation which is shown to be clockwise in FIG. 8. The outer end portion 79 has an axial length approximately equal to the axial length of the inner end portion 77 and is always opposed to the inlet port 69, notwithstanding piston reciprocation. Accordingly, the inlet port 69 will be open whenever the flat 87 travels past the port 69 (for almost 180 degrees of rotation) and is closed during rotary movement of the cylindrical portion surface 91 past the inlet port 69 (during about a little more than 180 degrees of travel).

As already indicated, respective means 47 and 49 are provided for rotating the piston 43 and for reciprocating the piston 43 within the bore 59 within an axial range having a maximum axial extent of about the axial length of the inner end portions 77 and 79 respectively of the piston 43. More specifically, while various arrangements can be employed, in the disclosed construction, the means 47 for rotating the piston 43 comprising a worm 93 on the engine output shaft 21 or on some other shaft driven by the engine 19 and a pinion 97 on a part 99 of the piston 43 remote from the pumping chamber 41 and in mesh with the worm 93 for effecting piston rotation at a reduced speed as compared to engine speed. The connection of the pinion 97 with the piston part 99 provides common rotary movement while affording axial movement of the piston 43 relative to the pinion 97 to accommodate piston reciprocation.

While various arrangements can be employed to reciprocate the piston 43 in response to piston rotation

and to vary the length of travel of piston reciprocation, or the distance through which the piston reciprocates, and thereby to vary the quantity of oil pumped independently of the rate of piston rotation, in the disclosed construction, such means includes a ring member 111 (See FIGS. 2, 4, and 5) adjustably pivotally mounted on a stud 113 on the frame 17. The ring member includes a bore 117 receiving another part 119 of the piston 43 remote from the chamber 41. Extending radially from the piston part 119 is a follower pin 121 which is received (See FIG. 4) in an interior annular groove 123 located in the bore 117 of the ring member 111 in a single transverse plane. Accordingly, when the ring member 111 is located on the pivot or stud 113 with the annular groove 123 perpendicular to the axis of piston rotation, such piston rotation will be ineffective to cause piston reciprocation. However, when the ring member 111 is pivoted from such perpendicular relation, the groove 123 then has an axial extent relative to the piston 43 and circular movement of the follower pin 121 in the groove 123 will cause piston reciprocation proportionate to the angular displacement of the ring member 111 from the position in which the groove 123 is perpendicular to the piston axis. Preferably, the ring member 111 includes a pointer 127 which is movable relative to a scale 129 located on the frame 17 and having suitable indicia so as to inform the operator of the extent of the reciprocating movement or the quantity or amount of oil being pumped in response to piston rotation.

Means in the form of a set screw 131 (See FIG. 5) can be used to releasably retain the ring member 111 at any desired angular setting relative to the setting shown in full lines in FIG. 4.

While various arrangements can be employed, in the disclosed construction, the before mentioned signal generating means includes the before mentioned plunger 67 which serves the dual purpose of assisting in closing one end of the pumping chamber 41 and acting as a switch operator or actuator. More particularly, the bore 59 includes, at the plunger end thereof, two related counterbores 133 and 137 (See FIG. 3) with the inner counterbore 133 having a greater diameter than the bore 59. In addition, the plunger 67 includes a collar or sleeve 139 which is reciprocally guided in the inner counterbore 133 and which serves as a seat for means in the form of a spring 141 for biasing the plunger 67 inwardly toward the pumping chamber 41. At its outer end, the spring 141 is seated against a plug 143 which is threadedly received in the outer counterbore 137 and which includes a central aperture 147 through which the plunger 67 extends and is guided for reciprocation.

The outer end 149 of the plunger 67 contacts a switch blade or contact member 151 forming a part of the normally closed switch means 53 which is operative to supply current to the indicating light 51 from a source of current. While various current sources can be employed, in the disclosed construction, the magneto 22 generates current to energize the light whenever the engine 19 is operating and the switch means 53 is closed, thereby to signal the operator that there is a lack of oil in the pumping system.

Means are provided between the pumping chamber 41 and the plunger 67 for immediately subjecting the

plunger 67 to pumping pressure during the inward movement of the piston 43 relative to the pumping chamber 41 by affording relative free flow from the pumping chamber 41 toward the plunger 67 and for restricting oil flow from in front of the plunger 67 back to the pumping chamber 41 when the piston 43 is retracting to afford supply of oil into the pumping chamber 41 from the reservoir 29 through the inlet port 69. Thus, the plunger 67 will not move away from an extended position retaining the switch means 53 opened unless low pressure exists in the pumping chamber 41 for a time interval far greater than the time interval of one half of the piston reciprocation cycle. As a result, the plunger 67 is insensitive to the withdrawal stroke of the piston 43 relative to the pumping chamber 41 but does sense a continued low pressure condition occurring over a duration including several cycles of piston reciprocation. Under such continued conditions of low pressure, the spring 141 will urge the plunger 67 inwardly, thereby permitting the switch means 53 to close and illuminating the light 51 indicating absence of oil flow.

While various arrangements could be employed, in the disclosed construction, the means for regulating or controlling oil flow between the pumping chamber 41 and the area immediately in front of the plunger 67 comprises a rigid disc 161 (See particularly FIG. 7) which is located adjacent to the end of the bushing 61 adjacent to the pumping chamber 41, and which has therein a relatively restricted central aperture 163. Retained between the disc 161 and the adjacent end of the bushing 61 is a flexible member 165 which is suitably apertured as, for instance, by a centered slit 169, or by centered cross slits, to permit relatively free deflection into the bushing bore for relatively unrestricted oil flow through the aperture 163 in the disc 161 in response to higher pressure in the pumping chamber 41 than in the area ahead of the plunger 67. Such capacity for unrestricted flow will cause the plunger 67 to be extended to open the normally closed switch means 53. However, when the pressure in the pumping chamber 41 is temporarily less than in the area ahead of the plunger 67 as, for instance, when the piston 43 is being withdrawn from the pumping chamber 41 during the intake stroke, the restricted aperture 163 in the disc 161 serves to prevent such flexure of the flexible member 165 as to afford relatively free oil flow through the aperture 163 in the disc 161. Accordingly, during a single piston withdrawal from the pumping chamber 41 on the intake stroke, there is insufficient bleed-off of pressure from the area in front of the plunger 67 to the pumping chamber 41 to permit such inward movement of the plunger 67 under the influence of the spring 141 as would permit closing of the switch means 53. However, should the condition of low pressure continue over a timer interval of several reciprocation cycles, sufficient flow through the slit or slits 169 in the flexible member 165 and through the central aperture 163 in the disc 161 will occur to afford inward displacement of the plunger 67 by the spring 141 and consequent closing of the switch means 53 to illuminate the light 51 and to indicate to the operator the absence of oil flow through the pumping arrangement to the outlet 37 at the cutter bar 23.

The pumping and signaling operation is as follows: When the piston 43 is fully retracted or withdrawn, both the inlet and outlet ports 69 and 71, respectively, are closed and the outlet port 71 is located for the particular reciprocation range (See FIGS. 8 and 8A) at a maximum distance from the end of the flat 81 adjacent to the cylinder portion 73. In addition, the spring 141 biases the plunger 67 to a fully inserted position within the bushing 61. Upon piston rotation, the piston begins to advance into the pumping chamber 41. During the first 45 to 60 degrees of movement (See FIGS. 9 and 9A), the piston moves approximately one-fourth of its full stroke while both the inlet and outlet ports 69 and 71 are closed. Because of the incompressibility of the oil, the volume of oil defined by this one-fourth stroke is forced into the bushing 61 and extends the plunger 67 to open the switch means 53 preventing illumination of the light 51. When the piston has rotated at least about 45 degrees, the flat 81 begins to travel past the outlet port 71 (See FIGS. 10 and 10A) and as the piston 43 continues movement inwardly of the pumping chamber 43, the oil in the pumping chamber 43 travels past the outer and inner flats 87 and 81, respectively, and out the outlet port 71. When the piston has rotated about 180 degrees from its starting position (See FIGS. 11 and 11A), the piston 43 is fully inserted within the pumping chamber 41 and the outlet port 71 is closed. During the first 180 degrees of rotation, the inlet port 69 has remained closed due to blockage by the surface 91. However, as the piston 43 continues its rotation and begins its withdrawal, the inlet port 69 is opened (See FIGS. 12 and 12A) to permit flow into the area in front of the flat 87 and into the pumping chamber 41 in general.

The inlet port 69 remains open until just less than 360 degrees of rotation until the piston 43 is fully withdrawn and is closed upon full withdrawal of the piston 43. As already explained, flow restriction provided by the disc 161 and flexible member 165 permit retention of pressure oil in the bushing 61 to retain the switch means 53 in open position until pressurized oil is again generated in response to piston movement inwardly of the pumping cylinder. Accordingly, it is seen that the disclosed arrangement provides periodic pumping from the inlet to the outlet and also serves to retain the switch means 53 in the off or open position so long as there is ample oil in the system. However, should air enter into the pumping chamber 41, inward movement of the piston 43 is insufficient to cause enough pressure to effect and maintain withdrawal of the plunger 67 and consequent opening of the switch means 53. Under these circumstances, the switch means 53 will be closed and the light 51 will be illuminated to notify the operator of a lack of oil in the pumping system.

Another pumping arrangement 175 embodying various of the features of the invention is shown in FIG. 15. The pumping arrangement 175 includes a housing 177 defining a pumping chamber 179 having a closed end. Received in the pumping chamber 179 is a pumping piston 181 which includes a single flat 183 subtending an angle of about 150 degrees and which is rotatably and reciprocably driven in the pumping chamber 179 relative to diametrically opposed inlet and outlet ports 185 and 187, respectively.

The outlet port 187 communicates through a duct 189 with one end of a cylinder 191 having therein a piston 193 operably connected to a signaling flag 195 which is mounted for pivotal movement on a stud 197 extending from the housing 177 and which includes a flag portion 199 and an arm 201 extending from the stud 197 in the opposite direction from the flag portion 199.

Means in the form of a leaf spring 203 engaged between the housing 177 and the flag portion 199 of the flag 195 is provided for biasing the flag portion 199 out of a pocket 205 in the housing 177 and in the clockwise direction to a position which can be readily seen by the operator and so as to engage the arm 201 against a protuberance or lug 207 on the other end of the piston 193, thereby urging the piston 193 inwardly of the cylinder 191 and to a position closing a delivery port 211 and connected duct 213 extending radially from the cylinder 191.

In operation of the arrangement or system shown in FIGS. 15 and 16, rotative and reciprocating movement of the piston 181 causes a pumping action in the pumping chamber 179 and the consequent oil flow through the outlet port 187 and into the cylinder 191. Such flow causes the piston 193 to be displaced to the right as shown in FIG. 15, against the action of the spring 203 to communicate the exhaust or outlet port 187 of the pumping chamber 179 with the delivery duct 213 and, at the same time, to displace the flag portion 199 into the pocket 205 and generally out of the view of the operator. Failure of retraction of the flag portion 199 into the pocket 205 indicates to the operator the absence of oil in the pumping system.

Various of the features of the invention are set forth in the following claims.

What is claimed is:

1. An oil pumping arrangement comprising a housing including a pumping chamber having opposite ends, a pumping piston extending into said pumping chamber from one of the ends thereof, means for rotating said piston in said pumping chamber, means for reciprocating said piston in said pumping chamber, in response to piston rotation, whereby to effect pumping operation incident to said reciprocating and rotary action, and signal means communicating with said pumping chamber and responsive to the failure of oil pressure therein and including a plunger extending into said pumping chamber from the other of said ends.

2. An oil pumping arrangement in accordance with claim 1 and further including means biasing said plunger inwardly of said pumping chamber.

3. An oil pumping arrangement comprising a housing including a pumping chamber having a main portion with a cylindrical shape, an inlet bore communicating with said pumping chamber, and an outlet bore communicating with said pumping chamber and being spaced axially of said pumping chamber and angularly from said inlet bore, a pumping piston extending into said pumping chamber and having a main portion with a diameter closely fitting said cylindrical shape of said pumping chamber, an inner end portion extending from said main portion and having a lesser cross sectional area than said main portion, and an outer end portion extending from said inner end portion and having a lesser cross sectional area than said inner end portion.

tion, whereby to effect pumping operation incident to said reciprocating and rotary action, and means communicating with said pumping chamber for signaling the failure of pressure within the oil in said pumping chamber.

4. An oil pumping arrangement comprising a housing including a pumping chamber, a pumping piston extending into said pumping chamber and including a part located externally of said pumping chamber, means for rotating said piston, a ring member having an internal bore receiving said piston part and including an internal surface with an annular groove therein, a follower extending radially from said piston part and received in said groove, and means mounting said ring member for adjustable angular positioning relative to said piston part about an axis transverse to the rotary axis of said piston, whereby to reciprocate said piston in response to rotation thereof and whereby to vary the stroke of reciprocation in response to angular adjustment in the position of said ring member.

5. An oil pumping arrangement comprising a housing including a pumping chamber, a pumping piston extending into said pumping chamber, means for rotating said piston in said pumping chamber, means for reciprocating said piston in said pumping chamber, whereby to effect pumping operation incident to said reciprocating and rotary action, a source of electrical power, an indicator light, normally closed switch means connecting said light to said power source, and means operably connected to said switch means for opening said switch means in response to oil pressure generated in said pumping chamber, whereby said indicating light is not illuminated when oil pressure is generated in said pumping chamber.

6. An oil pumping arrangement in accordance with claim 5 wherein said switch means includes a control member movable relative to a normally closed position, and wherein said means for opening said switch means includes an oil receiver, a plunger movable in said oil receiver and including a part engageable with said contact member to open said switch means in response to movement of said plunger in the direction outwardly of said oil receiver, and an oil flow connection between said oil receiver and said pumping chamber, said connection including means affording oil flow from said pumping chamber to said receiver and affording oil flow from said oil receiver to said pumping chamber which is restricted as compared to oil flow from said pumping chamber to said oil receiver.

7. An oil pumping arrangement in accordance with claim 6 wherein said means affording oil flow between said pumping chamber and said oil receiver includes wall means in said connection defining an aperture and a flexible member adjacent to said wall means and on the side thereof adjacent to said oil receiver and including means therein for affording a flow opening which is more restrictive by reason of the proximity of said wall means in response to oil flow from said oil receiver to said pumping chamber as compared to oil flow from said pumping chamber to said oil receiver.

8. An oil pumping arrangement in accordance with claim 6 including means biasing said plunger into said oil receiver.

9. A chain saw including a frame, an engine supported on said frame and including an output shaft, a

cutter bar extending from said frame, a saw chain trained around said cutter bar and driven by said engine; an oil supply duct having a discharge adjacent to said cutter bar, an oil reservoir supported by said frame and an oil pumping arrangement supported by said frame and including a pumping chamber operably communicating with said oil reservoir and said oil supply duct and having opposite ends, a pumping piston extending into said pumping chamber from one of the ends thereof, means for rotating said piston in said pumping chamber, means for reciprocating said piston in said pumping chamber in response to piston rotation including a gear connection between said output shaft and said piston, whereby to effect pumping operation incident to said reciprocating and rotary action, and signal means communicating with said pumping chamber and responsive to the failure of oil pressure therein and including a plunger extending into said pumping chamber from the other of said ends.

20 10. An oil pumping arrangement including a pump housing having an internal bore, an inlet bore communicating with said internal bore, and an outlet bore communicating with said internal bore and being axially and diametrically spaced from said inlet bore, a pumping piston extending into said internal bore from the end adjacent to said outlet bore for axial reciprocation and for rotation and having a main portion, an inner end portion extending from said main portion and having a lesser cross sectional area than said main portion, and an outer end portion extending from said inner end portion and having a lesser cross sectional area than said inner end portion, means for rotating and reciprocating said pumping piston relative to said housing, a plunger extending into said internal bore from the end adjacent to said inlet bore for axial reciprocation relative to said internal bore and subject to the pressure condition in said internal bore between said pumping piston and said plunger and having a part 30 extending from said housing, a source of electrical power, an indicator light, a normally closed switch connected between said power source and said light and including a contact member movable to open said switch in response to movement of said plunger outwardly of 40 said housing, and means biasing said plunger inwardly of said internal bore.

11. An oil pumping arrangement including a pump housing having an internal bore with an inlet, an outlet and spaced ends, a pumping piston extending into said internal bore from one of said ends for axial reciprocation and rotation, means for rotating and reciprocating said pumping piston relative to said housing, a plunger extending into said internal bore from the other of said ends for axial reciprocation relative to said internal bore and subject to the pressure condition in said internal bore between said pumping piston and said plunger and having a part extending from said housing, and signal means operated by movement of said plunger relative to said pump housing.

55 12. An oil pumping arrangement in accordance with claim 11 and further including means biasing said plunger inwardly of said internal bore and wherein said signal means includes a source of electrical power, an indicator light and a switch connected between said power source and said light and including a contact member movable to actuate said switch in response to movement of said plunger outwardly of said housing.
